CLAIM

The ornamental design for a cough spread control device, as shown and described.

DESCRIPTION

FIG. 1 is a top, rear, and left side perspective view of a cough spread control device having a body and an end cap; FIG. 2 is a bottom, rear, and right side perspective view thereof;

FIG. 3 is a front view thereof;

FIG. 4 is a rear view thereof;

FIG. 5 is a top view thereof;

FIG. 6 is a bottom view thereof;

FIG. 7 is a front and left side perspective view of the body of the cough spread control device, shown separated for ease of illustration;

FIG. 8 is a left side view thereof;

FIG. 9 is a right side view thereof;

FIG. 10 is a right side perspective view of the end cap of the cough spread control device, shown separated for ease of illustration; and,

FIG. 11 is a left side view thereof.

The broken lines in the drawings depict portions of the cough spread control device that form no part of the claimed design.

1 Claim, 5 Drawing Sheets
